United States Patent Office

Des. 184,414
Patented Feb. 10, 1959

184,414

FURNITURE GLIDE

Julius B. Wilhelm, Nantasket, Hull, Mass.

Application October 6, 1958, Serial No. 52,872

Term of patent 14 years

(Cl. D10—6)

Fig. 1.

Fig. 2.

Fig. 1 is a top plan view of a furniture glide embodying my new design; and

Fig. 2 is a view in side elevation of the furniture glide of Fig. 1.

I claim:

The ornamental design for a furniture glide, as shown.
